COMBINED DIAL AND HANDS FOR A WATCH

Lester E. Rubenstein, 100 E. Hartsdale Ave.,
Hartsdale, N.Y. 10530

Filed Feb. 13, 1974, Ser. No. 434,828

Term of patent 3½ years

Int. Cl. D10—07

U.S. Cl. D10—126

FIG. 1

FIG. 2

FIG. 1 is a front elevational view of a combined dial and hands for a watch showing my new design;

FIG. 2 is a typical side elevational view thereof;

Portions of the dial are shaded for color and the rear of the dial is plain and unornamented.

I claim:

An ornamental design for a combined dial and hands for a watch, as substantially shown and described.
